UNITED STATES PATENT OFFICE.

JOHN F. O'CONNOR, OF CHICAGO, ILLINOIS, ASSIGNOR TO WILLIAM H. MINER, OF CHAZY,
NEW YORK.

HAND-BRAKE FOR CARS.

1,300,467.

Specification of Letters Patent. Patented Apr. 15, 1919.

Application filed January 8, 1918. Serial No. 210,884.

To all whom it may concern:

Be it known that I, JOHN F. O'CONNOR, a citizen of the United States, residing at Chicago, in the county of Cook and State of Illinois, have invented a certain new and useful Improvement in Hand-Brakes for Cars, of which the following is a full, clear, concise, and exact description, reference being had to the accompanying drawings, forming a part of this specification.

This invention relates to improvements in hand brakes for cars.

The object of the invention is to provide a relatively simple and compact hand-operated brake for railway cars, having an increased or multiplied leverage, as compared with those types of hand brakes now commonly used, whereby a greater braking power is obtained for more effectively controlling movements of the cars.

In the drawing forming part of this specification, Figure 1 is a side elevation of a hand brake embodying my improvements. Fig. 2 is a vertical, sectional view, taken substantially on the line 2—2 of Fig. 1. Fig. 3 is another sectional view, taken substantially on the line 3—3 of Fig. 2. And Fig. 4 is a horizontal, sectional view, taken substantially on the line 4—4 of Fig. 1.

In said drawing, the brake is shown as including a substantially cylindrical hollow housing casing or casting 10 having a plurality of extended ears 11—11 by which it is adapted to be riveted or bolted to a wall of the car. Said casting 10 is provided with an inner wall 12 and an intermediate wall 13. The wall 12 is provided with a bearing 14 for the inner journal 15 of a chain winding drum 16. The intermediate wall 13 is also provided with a somewhat larger bearing 17 for a corresponding journal portion 18 of said drum 16.

To the outer side of the wall 13, the drum 16 is provided with a disk-like section 19 having a peripheral flange 20, the latter having integrally formed on its interior an internal gear 21. The winding drum 16 is also provided with a hollow shaft or axle section 22 on which is rotatably mounted a pinion 23. Also mounted on said axle section 22 is an oscillatably supported link 24, to the bottom of which is pivotally connected as at 25, an operating lever 26. The operating lever normally hangs in the depending position shown in Figs. 1 and 3 under the in-

fluence of gravity, and when in such position, the pawl 27 thereof is disengaged from the pinion 23. The lever 26 has also an extension 28 for guiding purposes and to also cover to some extent the recess or opening 29 formed in the casting 10 to permit the movements of the oscillating operating lever 26.

Secured to the casting 10 at its outer end is a cover plate 30 suitably flanged around its periphery, as indicated at 31, to fit within the casting 10, said plate being held in operative position by means of a bolt 32. On its interior, said plate 30 is provided with a stud bearing 33 on which is rotatably mounted a pinion 34 that meshes with both the pinion 23 and the internal gear 21.

A gravity controlled locking dog 35 is pivotally mounted on a suitable stud 36 on the inner face of the plate 30, the locking dog 35 engaging the pinion 23 to hold the chain in its tightened or wound condition. The chain is of course, released by merely swinging the dog upwardly, as will be understood.

The casting 10 is also suitably cut away at the bottom, as indicated at 37, to accommodate the brake chain 38, the upper link 39 of the latter being caught over a hook 40 formed integrally with the drum 16, the hook 40 being so arranged that when the link 39 is in place and the bolt 32 applied, said link 39 cannot be removed, as will be clear from an inspection of Fig. 2.

With the arrangement above described, it is evident that the chain can be tightened step by step with a pawl and ratchet effect by merely oscillating the lever handle 26. By interposing the pinions 23 and 34 between the operating lever and the internal gear 21, I am enabled to increase the leverage applied by the operator to any desired extent within reasonable limits, the leverage ratio increase shown in the drawing being substantially 3:1. The release of the chain can be effected by disengaging the locking dog as hereinbefore described. It will also be noted that by arranging the gearing mechanism in the manner shown and described, the entire device is made very compact and all the parts are well protected from the weather and injury in any other manner.

I claim:

1. In a hand brake adapted for railway cars and the like, the combination with a

housing of substantially cylindrical form having an outer end wall and an intermediate partition, of a chain winding drum rotatably mounted within said casing and adapted to receive the chain thereon in the space between said intermediate partition and the inner end of the casing, a gear wheel movable in unison with said drum, an oscillatable pawl lever, a ratchet pinion with which said pawl lever is adapted to coöperate, a pinion interposed between said ratchet pinion and said gear, and means for locking said drum against accidental reverse rotation, said gear wheel, pawl lever, ratchet pinion and pinion being all disposed within the casing in the space provided between said outer end wall and intermediate partition.

2. In a brake adapted for attachment to

railway cars and the like, the combination with a casing adapted to be secured to a car wall, said casing being divided into one relatively small chamber and another relatively large chamber, of a chain winding drum rotatably mounted within said casing and adapted to have the chain wound thereon within the larger chamber, an operating handle pivotally supported so as to swing within said smaller chamber, and leverage ratio multiplying gearing operatively interposed between said handle and said drum and all located within said smaller chamber.

In witness that I claim the foregoing I have hereunto subscribed my name this 29th day of Dec. 1917.

JOHN F. O'CONNOR.
